(57) **CLAIM**

The ornamental design for a portion of display panel or screen with animated graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a portion of a display panel or screen with a first image of an animated graphical user interface showing our new design; and, FIG. 2 is a second image thereof.

The appearance of an image transitions sequentially between FIGS. 1 and 2. The process or period in which an image transitions to another forms no part of the claimed design. The unevenly spaced broken lines shown in the drawings represent the portion of the display panel or screen with animated graphical user interface that are boundaries of the claimed design and form no part of the claimed design. The broken lines showing color in the animated graphical user interface form part of the claimed design.
